UNITED STATES PATENT OFFICE.

FRANK WILLIAM FICK, OF MANEYS CORNERS, AND PHILLIP SIMON VAN WIE, OF AMSTERDAM, NEW YORK.

APPLIANCE AND FIXTURE FOR RAILROAD RAILS AND TIES.

No. 818,875.

Specification of Letters Patent.

Patented Feb. 27, 1908.

Application filed September 22, 1904. Serial No. 225,541.

To all whom it may concern:

Be it known that we, FRANK WILLIAM FICK, residing at Maneys Corners, and PHILLIP SIMON VAN WIE, residing at 331 Locust 5 avenue, city of Amsterdam, Montgomery county, New York, citizens of the United States, have invented a new and useful Appliance and Fixture, of which the following is a description.

10 This invention relates to certain new and useful improvements in railway-rail fasteners.

The invention has for its object the production of a simple and inexpensive device of this character by means of which the rail 15 may be securely fastened in position upon the tie, whereby spreading of the rails and other accidental displacement thereof are prevented.

The invention will be hereinafter fully set 20 forth, and particularly pointed out in the claims.

In the accompanying drawings, Figure 1 is a side view illustrating our invention. Fig. 2 is a plan view thereof. Figs. 3 and 4 are enlarged side and plan views, respectively, of the flange-block. Fig. 5 is a view of the hook member. Figs. 6, 7, and 8 are details. Fig. 9 is a side view, and Fig. 10 a plan view, of a modification. Figs. 11 to 16, inclusive, are 30 details.

Referring to the drawings, A designates a flange-block, which is preferably mitered into the tie T and securely fastened to the latter by lag-screws D. The forward end of block 35 A is provided with an overhang a, adapted to project over the flange of rail R and engage the side or shank of the latter, whereby said rail is free for slight vertical play. The sides of block A are also provided with grooves b, 40 which converge to form a recess or chamber d, as shown.

Extending beneath the rail R and along the sides of the tie T are the arms e of a yoke-like hook member B, said arms entering 45 grooves b in such manner that the stem f of said hook member is located in the chamber or recess d. Said stem protrudes beyond the rear end of block A and is threaded to receive a nut F, a washer being interposed between the latter and the end of the block A. Said washer is preferably formed of two metallic members E, with an interposed cushion C, of elastic material, such as rubber.

In Figs. 9 to 16 we have shown a modified

form of our rail-fastener adapted for use in 55 connection with metallic ties. In this form the block A' is provided with bosses a', adapted to fit in recesses in the tie, bolts D' and nuts G being employed to secure the block in position. Said block is provided with a longitudinal chamber d', arranged to receive the shank of a hook-bolt B', said shank being threaded and united to block A' by nut F and washers E in the manner heretofore described.

In practice the flange-block is secured in 65 position and the hook-bolt passed under the rail to engage the inner flange thereof. By tightening up the nut said rail is securely clamped between said flange-block and hook-bolt and held rigidly from lateral play. 70

The advantages of our improved rail-fastener are apparent to those skilled in the art to which it appertains. It will be particularly observed that the same is simple in construction, is readily applied, and provides 75 means whereby liability of accidental displacement of the rail is reduced to a minimum.

We claim as our invention—

1. A device of the character described comprising a block one end of which is provided with an overhang adapted to engage the side of a rail, whereby vertical adjustment of the latter is permitted, and an adjustable hook-bolt carried by said block. 80

2. A device of the character described 85 comprising a block one end of which is provided with an overhang adapted to engage the side of a rail, whereby vertical adjustment of the latter is permitted, a hook-bolt carried thereby, and means for adjusting said bolt relatively to said block. 90

3. A device of the character described comprising a block one end of which is provided with an overhang adapted to engage the side of a rail, whereby vertical adjustment of the latter is permitted, said block being provided with a chamber or recess, and an adjustable hook-bolt having a stem located in said chamber or recess. 95

4. A device of the character described 100 comprising a block one end of which is provided with an overhang adapted to engage the side of a rail, whereby vertical adjustment of the latter is permitted, said block being provided with a chamber or recess, a hook-bolt having a threaded stem located in said chamber or recess, and a nut working on said stem. 105

5. A device of the character described comprising a block one end of which is provided with an overhang adapted to engage the side of a rail, whereby vertical adjustment of the latter is permitted, said block being provided with a chamber or recess, a hook-bolt having a threaded stem located in said recess, a nut working on said stem, and a cushioned washer interposed between said nut and said block.

6. A device of the character described comprising a block one end of which is provided with an overhang adapted to engage the side of a rail; whereby vertical adjustment of the latter is permitted, means for securing said block to a tie, a hook-bolt and means for clamping said bolt against the rail.

7. A device of the character described comprising a flange-block provided with converging grooves terminating in a chamber or recess, a yoke-like hook-bolt having arms located in said grooves, and a stem located in said chamber or recess, and means for adjusting said bolt relatively to said block.

In testimony whereof we have hereunto signed our names to this specification in the presence of two subscribing witnesses.

FRANK WILLIAM FICK.
